[57] CLAIM

The ornamental design for an automobile shaped vacuum cleaner, as shown and described.

DESCRIPTION

FIG. 1 is a top perspective view of an automobile shaped vacuum cleaner showing our new design;

FIG. 2 is a front elevational view thereof;

FIG. 3 is a side elevational view thereof;

FIG. 4 is a rear elevational view thereof;

FIG. 5 is a top plan view thereof; and

FIG. 6 is a bottom plan view thereof;

The electric cord is shown broken away in FIGS. 1, 3, 4, 5 and 6 for ease of illustration and is understood to represent indeterminate length.

FIG. 1

FIG. 2

FIG. 3

FIG. 4

FIG. 5

FIG. 6
